UNITED STATES PATENT OFFICE.

JAN CORNELIS LOKKER, HENDRIK FILIPPO, AND PANCRAS SCHOONENBERG, OF EINDHOVEN, NETHERLANDS, ASSIGNEES TO GENERAL ELECTRIC COMPANY, A CORPORATION OF NEW YORK.

ELECTRIC LAMP.

Application filed February 14, 1923, Serial No. 618,966, and in the Netherlands February 28, 1922.

Our invention relates to electric lamps having light-diffusing globes, of the white color type. It relates also to the method of manufacturing globes.

5 In the manufacture of glass globes for electric lamps heretofore, a kind of glass has been used which is of a white color and which diffuses the light. Such glass is known as bone-glass.

10 It appears that bone-glass has a bad effect on the life of a lamp, but we have found that glass globes with light-diffusing bone-glass may be made without this bad effect. This can be done by making glass globes of 15 two layers, which are melted together; the inner layer consists of ordinary clear-glass, whereas the outer layer is formed of white colored light-diffusing bone-glass. With 20 a construction above indicated, we have found that the life of such a lamp is practically the same as that of lamps having globes of the ordinary clear-glass, so that with this invention a considerable improvement is obtained.

25 In the accompanying drawing a lamp is illustrated which is provided with a glass globe according to the invention.

The glass globe of the lamp may be of the gas filled type which consists of two 30 layers. The inner layer 1 is of clear-glass, for example, of a kind ordinarily used in the manufacture of electric light globes, whereas the outer layer 2 is formed of glass of the light-diffusing type preferably of the well known bone-glass.

35 Inside the globe the glowing body 4 or film is connected to the lead-in wires 5 and 6 which pass through the glass stem 3 as is usually the case. This stem may be made 40 of the ordinary clear-glass. As shown in the drawing, the inner part of the lamp is completely insulated or separated from the bone-glass, so that the prejudicial results which occur in lamps using bone-glass as 45 ordinarily constructed do not appear in lamps with globes made according to the invention.

Glass globes for the electric lamps according to the invention may be manufac-

tured in accordance with a method which is 50 only slightly more complicated than the method of manufacture of globes of clear-glass alone. According to the invention the lower part of the blow pipe with which the globe is blown is first immersed in a bath 55 of ordinary clear-glass, after which it is immersed in a bath of bone-glass. The mass of glass is then blown into a globe in the ordinary way. In other words, the invention may be practiced by obtaining on the 60 end of the blow pipe a "gather" of glass which is shaped by rolling over an iron plate, as is the common practice, to give the mass a definite shape and to cool its surface. This operation is known as "marvering". The marvered gather may then be 65 dipped into the other kind of glass, bone-glass for example, and again marvered so as to distribute a second glass evenly over the first after which the gather may be 70 blown in the usual way.

It will be obvious that the invention may be also practiced in connection with automatic glass blowing machines. It is to be observed that the globes can be used for 75 electric glow lamps as well as for luminescent lamps, discharge lamps with tungsten electrodes and the like.

What we claim as new and desire to secure by Letters Patent of the United States is,— 80

1. An electric lamp having a bulb consisting of two layers which are melted together, the inner layer consisting of clear-glass and the outer layer of a light-diffusing glass.

85 2. An electric lamp having a bulb consisting of two layers which are melted together, the inner layer consisting of clear-glass and the outer layer of a light-diffusing glass, said light-diffusing glass being bone-glass.

90 In witness whereof, we have hereunto set our hands this thirty-first day of January, 1923.

JAN CORNELIS LOKKER.
HENDRIK FILIPPO.
PANCRAS SCHOONENBERG.
